ART OF MAKING METAL VISES.

No. 394,540.

Patented Dec. 11, 1888.

UNITED STATES PATENT OFFICE.

RICHARD JOHNSON, OF FREEPORT, ASSIGNOR TO FREDERICK C. AUSTIN, OF CHICAGO, ILLINOIS.

ART OF MAKING METAL VISSES.

SPECIFICATION forming part of Letters Patent No. 394,540, dated December 11, 1888.

Application filed June 18, 1888. Serial No. 277,490. (No model.)

To all whom it may concern:

Be it known that I, RICHARD JOHNSON, a citizen of the United States, residing at Freeport, in the county of Stephenson and State 5 of Illinois, have invented a certain new and useful Improvement in the Art of Making Metal Vises, of which the following is a specification.

My invention relates to the production of 10 metal vises, involving, as a matter of construction, a pair of wrought-iron or soft-steel standards provided with steel-faced jaws and connected together by means of a flat lug projecting from one standard and pivotally held 15 between a couple of correspondingly-formed lugs, which likewise project laterally from the other standard.

The practice of forging and finishing by a 20 succession of manual operations the said component members of vises has been slow, laborious, and expensive, and while requiring the employment of skilled labor has failed to produce uniformly-finished work, and has further failed to produce such uniformity of 25 shape and construction as would at all times permit one of the such members finished up by a workman for one vise to be interchanged with a corresponding member destined by the same or some other workman for another 30 vise.

The objects of my invention are to overcome all of the foregoing defects and objectionable features heretofore incident to the hand-forging and hand-finishing of such metal 35 vises; to avoid the frequent reheatings heretofore necessary; to produce said articles in a rapid, economical, and accurate way; to provide a better article, and to render the production of the vises a commercial success.

40 To illustrate my improvement, Figure 1 of the annexed drawings represents in perspective the upper portion of a blank or partially-formed vise-standard, and indicates in dotted lines a block or blank and face-plate piled 45 thereon. Fig. 2 represents in perspective the aforesaid blank, and Fig. 3 is a like view of the aforesaid face-plate. Fig. 4 represents a small block designed to form a knob on the back of the upper jaw portion of the vise- 50 standard. Fig. 5 is a perspective view of one

of the dies, which in Fig. 7 constitutes the lower die. Fig. 6 is a top plan view of said lower die, E, and represents in dotted lines the position to be occupied by the mandrel G of Fig. 7. Fig. 7 is a section taken on a vertical plane through both dies brought together, and indicates the standard having its jaw portion formed by the union of the blank or partially-formed vise-standard shown in Fig. 1, with blank B and face-plate C, as herein- 60 after set forth. Fig. 8 represents in perspective the upper die, E, of Fig. 7, the acting face portion of said die being underneath in accordance with the proper position. Fig. 9 represents in side elevation the jaw portion 65 of the vise-standard of Fig. 7 placed between the finishing-die portions H and H'. Fig. 10 shows in perspective the upper finished jaw portion of the vise-standard. Fig. 11 shows the vise in elevation. Fig. 12 represents a 70 portion of the vise-standard, broken for convenience of illustration, and shows the relative position of the two blanks or plates I that are to be welded thereto to form lugs for a pintle. Fig. 13 shows in perspective the 75 lower die, and Fig. 15 is a like view of the upper die for welding plates I to the vise-standard. Fig. 14 shows in cross-section said two dies brought together with the plates I welded to the vise-standard and a mandrel, M, be- 80 tween certain portions of the plates, the line of section being transverse to the length of the vise-standard. Fig. 16 shows in perspective a portion of the vise-standard with the plates of Fig. 12 welded thereto, so as to form 85 lugs a^2 . Fig. 17 is a perspective view of one, and Fig. 18 a perspective view of another, of a pair of dies for finishing the vise-standard. Fig. 19 is a section taken on a vertical plane through the dies of Figs. 17 and 18 brought 90 together, with the block N (shown in dotted lines, Fig. 17) piled on the vise-standard and welded to the same. Fig. 20 shows the lower portion of the short vise-standard, having a lug, a^3 , formed by welding the aforesaid blank 95 or block N to the vise-standard.

In carrying out my invention I provide in any suitable way a set of blanks, such as shown in Figs. 1, 2, 3, and 4, wherein A is a metal blank which is to form one of the 100

vise-standards *a* and the body portion *a'* of the jaw thereon; B, a metal blank which is to form the projecting gripping portion of the jaw; C, a steel plate which is to provide a facing for said gripping portion of the jaw, and D a metal block which is to form upon the rear side of the body portion of the jaw a knob, which, while not strictly necessary to the construction and operation of a vise, is invariably demanded by the trade as a matter necessary to its finish. These four blanks are piled together at a welding heat within a die, E, (such as shown in Figs. 5, 6, and 7,) and while at a welding heat united by the conjoint action of said die E and a die, F, which latter is represented in Figs. 7 and 8. The mode of piling together the four blanks A, B, C, and D will be understood by referring to Fig. 7, wherein the separation of the blanks from one another preparatory to the operation of uniting them into a single piece is indicated by dotted lines. The action of the dies E and F serves to unite the blanks and properly shape the jaw, which, when shaped, will appear substantially as in Fig. 10. Preparatory to bringing the dies together a mandrel, G, Fig. 7, may be fitted within the hole *a²*, which is formed through the standard portion *a* of the blank A as an opening for the usual jaw-adjusting bolt.

After the blanks A, B, C, and D have been united to provide the standard with a properly-constructed jaw, the jaw is desirably subjected to the action of the edge-finishing dies H and H', which serve to obliterate such web as may have been formed by the action of the dies E and F.

The foregoing mode of operation requires no change in making either of the two jaws of a vise, whereby by repeated operations any desired number of vise-standards having uniformly-constructed jaws may be produced. In these vises one of the vise-standards is provided with a pair of laterally-projecting ears or lugs, *a²*, which are arranged parallel with one another, while the other standard is provided with a single laterally-projecting flat lug, *a³*, Fig. 11, adapted to enter the space between the said pair of lugs, so that by providing the lugs with pivot-holes the single lug can, by a suitable pivot, be hinged between the pair of lugs.

In order to provide vise-standards with the lugs *a²*, I provide a couple of metal blanks or plates, I, Fig. 12, and a vise-standard, heat all three to a welding heat, then pile them within a die K, (such as shown in Figs. 13 and 14,) and then by the conjoint action of the said die K and a die, L, (such as illustrated in Figs. 14 and 15,) unite the said blanks and standard, so as to provide the latter with the lugs *a²*, as shown in Figs. 11 and 16.

The proper relative position of the piled blanks I and standard is to some extent indicated in Fig. 12, but more accurately shown in Fig. 14, wherein the separation of the piled

blanks and standard preparatory to the union of the three is indicated by dotted lines. In said figure a steel mandrel, M, is shown placed between the projecting portions of the blanks I, in order to insure proper ultimate shape of the lugs and permit the dies to bevel the edges of the blanks.

As a means for providing certain other of the vise-standards with the single lugs *a³*, I first provide a vise-standard and a metal blank, N, which, as indicated in dotted lines, Fig. 17, consists of a rectangular block or plate, preferably beveled at one end. This blank N and the vise-standard are then heated to a welding heat and placed together in a die, P, as illustrated in dotted lines, Fig. 17, and then by the conjoint action of the die P and a die, P', as in Fig. 19, the blank and the standard are united, so as to provide the standard with the single lateral lug *a³*. (Shown in Figs. 11 and 20.) After uniting the blank N and the standard, the article should be subjected to the action of dies Q and Q', so as to remove any web which may have been formed in welding together the said blank and standard, and after producing a standard with a pair of lugs, *a²*, and a standard with a lug, *a³*, all of said lugs can be bored to provide them with suitable pivot-holes.

In Fig. 11 one of the standards is shown provided with an extension, *a⁴*, which, however, has no relation to my invention.

By the foregoing operation one workman can rapidly turn out vises, whereby the employment of several workmen, as heretofore incident to the old art, is avoided. The vises made in accordance with my improvement are also superior in uniformity of form and structure and have a far better finish than can be attained by hand-forging, and obviously much saving in time, labor, and expénsé is effected.

While the blanks C, which serve to face the vise-jaws, are made of steel, the remaining blanks are all made either of wrought-iron or soft steel, wrought-iron being, however, preferred. It will be obvious that the vise-jaws could be formed upon the standards without the knobs which the blanks D are intended to form upon the outer or rear sides of the jaws, and that after piling together the blanks A, B, and C, and uniting them as hereinbefore set forth, the knob could be subsequently applied. It will, however, involve greater economy in and rapidity of production to pile together the blanks A, B, C, and D in the first instance.

What I claim as my invention is—

1. The within-described improvement in the art of making vise-jaws, consisting in preparing the blanks A, B, and C, piling them together at a welding heat, and while at such heat uniting said blanks by die-pressure, substantially as set forth.

2. The within-described improvement in the art of making vise-jaws, consisting in preparing the blanks A, B, C, and D, piling them to-

gether at a welding heat, and while at such heat uniting said blanks by die-pressure, substantially as set forth.

3. The within-described improvement in the art of providing vise-standards with lugs a^2 , consisting in piling together at a welding heat a standard, a , and a pair of blanks, I , with a mandrel between the projecting portions of the lugs, and while at such heat uniting them by die-pressure, substantially as described.
4. The within-described improvement in the

art of providing vise-standards with the single lugs a^3 , consisting in piling together at a welding heat a standard, a , and a blank, N , and while at a welding heat uniting said blank and standard by die-pressure, substantially as set forth. 15

RICHARD JOHNSON.
